[57] CLAIM

The ornamental design for a threadless instant release bicycle tire pump connector, as shown and described.

DESCRIPTION

FIG. 1 is a perspective view of a threadless instant release bicycle tire pump connector showing my new design in closed position, in association with a pump hose and tire valve and the repositioned valve securing nut and tire rim and tire all of which are illustrated in broken lines for illustrative purposes only.

FIG. 2 is a side elevational view thereof in closed position; and

FIG. 3 is an end elevational view thereof.

FIG.1

FIG. 2

FIG. 3
